UNITED STATES PATENT OFFICE.

ISAAC P. FRINK, OF NEW YORK, N. Y.

REFLECTOR FOR CHANDELIERS, &c.

SPECIFICATION forming part of Letters Patent No. 274,930, dated April 3, 1883.

Application filed November 29, 1882. (No model.)

To all whom it may concern:

Be it known that I, ISAAC P. FRINK, a resident of New York, in the county and State of New York, have invented a new and useful Improvement in Chandeliers and Reflectors, of which the following is a specification.

My invention relates to an improvement in chandeliers and reflectors, wherein in the manufacture of single or double reflectors I combine a variety of elements not before used together for improving the illuminating action and effect of the reflectors. I also have improvements in the construction of reflector-frames; and my invention consists in the devices substantially as hereinafter set forth.

Figure 1 is a side elevation, partly in section. Fig. 2 shows a section of a solid frame; Fig. 3, a section of a skeleton frame. Fig. 4 is a cross-section, showing a solid frame, &c. Figs. 5 and 6 are details. Fig. 7 is a side elevation, showing in part a plain band and in part a corona about the base. Figs. 8, 9, 10, and 11 are detailed views. Fig. 12 is a horizontal sectional view of my device, showing the general relation of the reflecting-panels to one another.

In my construction of double reflectors I place in the outer reflector or frame, A, panels B, of translucent glass, or other semi-transparent material, colored or white, any shade or color that will reflect a part of the light inward and downward, and allow part of it to pass through the panel and give a measure of light—a quiet subdued light—out into the room above the reflector. These translucent panels will ordinarily be used in this outer reflector in a skeleton frame; but they may be used in a solid frame in combination with an inner reflector, and these translucent panels may be corrugated and used in solid or skeleton frames with or without combination with an inner reflector. The panels may be put in with alternate shades, or with white and colored panels; and the colored panels may be made from colored glass, or white glass flashed on one side, or with two panels of different colors, one lying on the other, as at Q Q, Fig. 12, according to the best effect to be produced; and these may be used without an inner reflector. In some cases I will use, in combination with an interior reflector, a plain opal panel, without other colors. In combination

with this exterior reflector I have an inner cone or reflector, C, carrying panels D, of any suitable material, to reflect the light outward; or they may be translucent, and in a frame allowing part of the rays to pass through them; and these panels, in a solid frame of an interior cone, may also be made in variety, as that they may be metallic reflectors, or silvered glass, plain or corrugated, or alternately plain or corrugated; or the reflecting-surfaces may be colored, or a colored panel be used in alternation with a plain or silvered one, according as they will be found to produce the best effect in combination with the exterior reflector. They may also, in this connection, be translucent. These reflectors may also be made in a single piece, molded or blown into the required form, and be used with a solid back, as shown in Fig. 12, or be translucent and put in a skeleton frame, to allow part of the rays to pass through.

It is evident that when the inner and outer reflecting-parts are constructed with angles, as shown in the drawings, panels are formed, which are either of plates detachable from those adjacent, or, as when the interior reflector is molded or blown in one piece, are integral with said adjacent panels.

It is evident that the metal backing or cone C, Fig. 12, may itself constitute the reflecting-surface, when, by reason of extreme heat or other causes, the panels D are undesirable and are dispensed with.

The exterior reflector, A, has at the upper edge, on the inside, a series of lips, E, of sheet metal, bent over inward, to engage the top of the panels. At the lower edge of the frame is a ledge, F, on which the panel will rest, and, extending below this ledge, is a section, S, of the same, bent up inward, leaving a space behind it to receive the edge of the plate G, which is held in place by the screws H or other suitable device; and this plate extends across the inside of the lower end of the panel and holds it in place. This greatly facilitates the putting in and taking out of panels in case of need. I have also, at the junction of the sides of the panels, an inside removable rib, I, made Ω shape transversely, (see Figs. 10 and 11,) and having the ends, respectively, fitted to catch under the lips E and be covered by the ends of the plates G; and when this plate is

removed the rib and the panel are readily taken out. The exterior reflector may be finished at base with a band, K, or, as seen at the right-hand end of Fig. 7, with a corona, 5 L, and either be worked out in any desirable pattern.

The frames may be in any desired shape, square, rectangular, polygonal, pyramidal, or conical, or a combination of any of these shapes.

10 I claim—

1. In a double reflector, the frame A, flaring away from the center at its base and carrying translucent or semi-transparent panels B, in combination with an interior reflector, 15 C, substantially as and for the purpose specified.

2. In a double reflector, the frame A, flaring away from the center at its base and carrying translucent panels of plain opal, or white glass 20 panels, in combination with an interior reflector, C, substantially as and for the purpose set forth.

3. The combination of an exterior reflector flaring away from the center at its base and 25 having panels of white or colored glass or other translucent material, and an interior metallic reflector, or reflector having therein panels of metal-plated glass, substantially as and for the purposes herein set forth.

30 4. The combination of an exterior reflector, substantially as above described, and the interior reflector, C, having translucent panels, substantially as set forth.

5. The combination of the exterior reflect-

or, substantially as above described, and an 35 inner reflector molded or blown in one piece, substantially as specified.

6. A reflector having a frame carrying translucent, or semi-transparent panels corrugated, substantially as and for the purpose set forth. 40

7. A reflector flaring away from the center at its base, having translucent panels of two or more colors, said colors either shown in the same panel or in panels lying side by side or one upon the other, substantially as set forth. 45

8. A reflector having translucent panels of which a part are corrugated and a part plain surface, substantially as named.

9. A reflector having panels of which a part are corrugated and a part plain surface, 50 substantially as specified.

10. An interior reflector having panels of which a part are corrugated and a part plain surface, in combination with an exterior reflector, substantially as set forth. 55

11. In a reflector-frame, the lips E, ledges F, and section S, in combination with the plates G, substantially as specified.

12. The ribs I, in combination with the lips E and plates G, substantially as set forth. 60

13. The exterior skeleton reflector-frame A, carrying translucent panels and provided at its base with a corona, I, substantially as and for the purpose specified.

ISAAC P. FRINK.
